(57) **CLAIM**

The ornamental design for a combination cup holder and drip catcher for liquid detergent dispensers and liquid fabric softener dispensers, as shown and described.

DESCRIPTION

FIG. 1 is a front perspective view showing my new design.

FIG. 2 is a rear perspective view thereof.

FIG. 3 is a top plan view thereof.

FIG. 4 is a plan bottom view thereof.

FIG. 5 is a front elevation view thereof.

FIG. 6 is a rear elevation view thereof.

FIG. 7 is a left side elevation view thereof, the right side view being a mirror image thereof.

FIG. 8 is a front exploded perspective view showing the hanger and tray parts of my new design.

FIG. 9 is a rear exploded perspective view thereof.

FIG. 10 is a top plan view of the hanger.

FIG. 11 is a bottom plan view thereof.

FIG. 12 is a front elevation view thereof.

FIG. 13 is a rear elevation view thereof.

FIG. 14 is a left side elevation view thereof, the right side elevation view being a mirror image thereof.

FIG. 15 is a top plan view of the tray.

FIG. 16 is a bottom plan view thereof.

FIG. 17 is a front elevation view thereof.

FIG. 18 is a rear elevation view thereof.

FIG. 19 is a left side elevation view thereof, the right side elevation view being a mirror image thereof; and,

FIG. 20 is a perspective view showing my new design holding a cup for dispensed liquid, and as installed onto the spout of a bulk liquid dispenser for laundry detergent and fabric softener, the cup and bulk liquid dispenser being shown in dashed lines and forming no part of the claimed invention.
